GAS BURNER

Smith E. Henson, Oklahoma City, Okla., assignor
of one-third to Carl L. Zeller and one-third to
A. P. Petway

Application February 3, 1932, Serial No. 590,715

1 Claim. (Cl. 158—104)

This invention relates to gas burners and has for its object the production of a simple and efficient gas burner which is provided with a plurality of substantially diamond-shaped air passages extending through the entire body, the body being provided with gas outlets communicating with the diamond-shaped openings for the purpose of mixing the gas with air and facilitating the heating of the burner.

Another object of this invention is the production of a simple and efficient burner which may be formed of cast iron or other similar material and which may be so constructed as to support the carborundum face plate, the face plate and body being provided with transversely extending air vents or openings extending entirely through the body and face plate, the body being provided with gas discharge openings communicating with these air vents.

A further object of this invention is the production of a simple and efficient burner which is cheap in construction, and which may be operated at a minimum cost, as it will operate efficiently on a gas pressure of approximately two ounces or more.

Other objects and advantages of the present invention will appear throughout the following specification and claim:

In the drawing:—

Figure 1 is a front elevation of the gas burner, a portion thereof being broken away and shown in section;

Figure 2 is an end elevation of the gas burner, a portion thereof being shown in section;

Figure 3 is a rear elevation of the gas burner;

Figure 4 is a section taken on line 4—4 of Figure 1, looking in the direction of the arrows;

Figure 5 is a section upon an enlarged scale taken on line 5—5 of Figure 4;

Figure 6 is an enlarged sectional view through a portion of the end wall of the burner showing the mounting of the expansion plug therein; and

Figure 7 is a section taken on line 7—7 of Figure 4.

By referring to the drawing, it will be seen that 1 designates the body which may be formed of cast iron or other suitable material having an enlarged centrally located collar formed thereon, and indicated by the numeral 2, from which projects a nipple 3, the nipple being internally threaded as at 4, for the purpose of receiving a gas supply pipe. The body 1 has one side or end wall formed with a transversely extending channel 5 which communicates with a pilot light pipe 6 for supplying gas to the channel 5, this channel 5 communicating with the outer face 7 of the burner as shown at

7 in Figure 5, and constituting a pilot light therefor.

The body 1 is provided with a plurality of closely arranged substantially diamond-shaped openings 8 which extend transversely through the body 60 and are surrounded by walls 9 extending from the rear wall 10 to the front wall 11 of the body 1, as shown clearly in Figure 4. These walls 9 will permit the gas to freely pass around through the channels 12 formed in the body between the various substantially diamond-shaped openings or air passages 8 and freely circulate through the body, the channels 12 communicating with the nipple 3 and supply pipe which is adapted to be threaded into the internally threaded nipple 3 shown in 70 Figure 2. The gas passes into the hollow body as shown by the arrows in Figure 2, and will then be free to circulate between the various diamond-shaped openings 8, or the walls 9 thereof, and be evenly distributed over the entire body. The walls 75 9 of the openings 8 are each provided with gas discharge openings or orifices 13 which preferably extend at an angle of approximately 45 degrees to the longitudinal axis of the openings 8, as shown in Figure 7. A dent 14 is formed in each wall 9 directly in advance of the discharge end of the gas opening or passage-way 13, as shown in Figure 7, for the purpose of causing the stream 80 of gas passing through the passage-way 13 to be broken up in a spray so as to be caught by the air passing through the openings 8 in the direction as shown by the arrows in Figure 7, and carried to the outer face of the carborundum plate 15.

As shown in Figure 4, the body 1 is provided with a forwardly extending outer flange 16 which carries an inner asbestos lining 17, and a flat carborundum plate 15, previously mentioned, is seated upon the front wall 11 of the body 1 and abuts against the asbestos lining 17, this asbestos lining 17 constituting an expansion joint to take up the expansion and contraction of the respective materials from which the body 1 and the plate 15 are made. The carborundum plate 15 is provided with registering substantially diamond-shaped openings 18 extending transversely thereof of which diamond-shaped openings 18 are adapted to register with and form a continuation of the openings 8 formed in the body 1.

The body is formed of cast iron and in each of its marginal walls 19 there is provided a threaded opening 20 within which a threaded plug 21 is positioned, the threaded plug 21 being provided with a squared or other socket 22 to facilitate the threading of the plug into position. The plugs are made of steel or any suitable ma-

100

95

105

110

terial which will permit expansion and contraction of the walls under the action of heat and cold without cracking the cast iron from which the frame is made.

- 5 From the foregoing description, it will be seen that a very simple and efficient as well as cheap burner construction has been provided which will constitute an efficient heating means, and it should be understood that the burner may be

10 supported in any suitable or desired manner.

By positioning the substantially diamond-shaped openings within the body of the burner in staggered relation to each other around the supply nipple 3, the front wall will have an unbroken intermediate portion in front of the nipple which will be struck by the gas entering the body and cause the gas to spread and be distributed throughout the interior of the body. It should be understood that the pilot light 7 may be located in any suitable or desired position upon the face of the burner without departing from the spirit of the invention and certain other detail changes in the mechanical construction may be employed also.

25 In carrying out this invention, it should be understood that the gas will pass in and through the body in the direction as indicated by the arrows in Figure 2, and upon striking the unbroken central portion of the front wall in front of the inlet be circulated around and between the va-

rious openings 8 and then discharged out through the gas discharge passageways or openings 13 into the passages 8 where it will be thoroughly mixed with air passing through the registering passages or openings 8 and 18 and carried toward the front of the carborundum plate 15 where the gas will be ignited and burn in the usual way.

Having described the invention, what is claimed as new is:

80 A gas burner comprising a hollow body of cast iron constituting a gas reservoir and having front and rear walls and marginal walls, a plurality of conduits extending through said body and opening through the rear wall and front wall thereof, said conduits having opposed side walls integrally united to the front and rear walls of the body, the walls of said conduits being each formed adjacent its front end with a gas discharge opening extending forwardly at an incline into the conduit and terminating in spaced relation to the front end of the conduit, the walls of said conduits being each also formed with an indentation located in front of and spaced forwardly from a discharge opening for breaking up streams of gas into a spray when discharged into the conduit, 85 steel plugs screwed into threaded openings formed through marginal walls of said body, and a pilot burner associated with said body.
